UNITED STATES PATENT OFFICE.

CYRUS W. ELROD, OF KANSAS CITY, MISSOURI.

CHECK-MARKER.

1,269,692.

Specification of Letters Patent. Patented June 18, 1918.

Application filed November 27, 1916. Serial No. 133,835.

To all whom it may concern:

Be it known that I, CYRUS W. ELROD, a citizen of the United States, residing at Kansas City, in the county of Jackson and State of Missouri, have invented certain new and useful Improvements in Check-Markers; and I do declare the following to be a full, clear, and exact description of the invention, such as will enable others skilled in the art to which it appertains to make and use the same, reference being had to the accompanying drawings; and to the figures of reference marked thereon, which form a part of this specification.

My invention relates to check markers and more particularly to a device of that character whereby amount indicating stubs may be formed along one edge of a check in order to properly identify the amount for which the check is drawn and thereby avoid uncertainty as to the amount of the check and obviate possible loss to the drawer.

In accomplishing this object I have provided a mechanical device embodying the improvement hereinafter described and illustrated in the accompanying drawings, wherein:

Figure I is a perspective view of the preferred embodiment of the invention, illustrating its use on a bank check.

Fig. II is an enlarged detail perspective of the device.

Fig. III is a transverse section thereof.

Fig. IV is a detail perspective of the preferred type of pointer.

Fig. V is a view of a check and its stub, showing the stub removed from the check body, and the edge portion of the check removed to form the amount identifying stub.

Referring more in detail to the drawings:

1 designates the body of the marker which is preferably constructed of flat spring metal having a straight edge portion 2 of sufficient length to extend over a check of ordinary size, and a guide member 3 which lies parallel with the straight edge portion 2 and is spaced theretrom so that a check may be received therebetween. The straight edge portion and back member are connected by an integral spring loop 4 that is adapted to hold the back and straight edge portions in their spaced relation, but to yield to enable a check to be gripped therebetween when the opposite members are pressed toward each other.

The straight edge portion 2 is provided with a longitudinal rib 5 which serves to stiffen the member and also to form a rail along which a slide pointer 6 may travel, in order that the pointer may be located over designated numerals along the edge of the check that is to be marked by the device.

The slide 6 comprises the arch 7 that overlies the rib 5 and is adapted for free sliding movement therealong to properly place the pointer on the numerals in marking the amount of the check to which the device is applied.

Extending from one edge of the arch 7 is an arm 8 that rides along the top of the body portion 2 and has a point 9 extending beyond the edge of said body portion to overlie a part of the check, so that when the check is pulled thereagainst a portion of the check is torn away to the contour of the point to leave a projection or stub on the edge of the check, the arm 8 being provided with the handle member 10 whereby the pointer may be easily moved along the body portion 2. Extending from the end of the arch 7 opposite the arm 8 is a lip 11 that projects under a flange 12 on the edge of the body portion 2 and is spaced therefrom to provide the slot 13 within which the said lip may ride, the spacing of the flange from the body portion 2 being sufficient to form a channel in which the lip may slide freely without loss of motion.

14 designates a check of a type especially adapted for use with the marker containing my improvements, and which carries along one edge thereof a row of numerals 15 which face with the check, and a column of numerals 16 wherein the numerals are arranged vertically in a column from end to end of the check, both the row and column of figures being provided, for the reason that as the body portion of the check marker is adapted to lie adjacent the row 15 with the point 9 of the slide overlying the row, and in position for indicating a particular numeral, that numeral is covered by the point 9 and cannot be seen by the user of the device. By providing the check with the column 16, the numerals of which are arranged correspondingly to those in the row 15, the point 9 may be directed to any desired number in the column 16 and when in that position will overlie a corresponding number in the row 15, so that when the edge of the check is torn away the numeral in the

column 16 indicated by the point will be exposed on the stub 17 on the edge of the check.

Assuming the device to be constructed as described, and to be used with a check of the character shown, when the check is made out in the ordinary manner the protecting device is placed over the body portion 2, overlying the face of the check along one edge thereof, the end of the check being slipped between the body portion 2 and back member 3 so that the check may be gripped by said parts to hold the same firmly. The slide 6 is then moved along the check until it comes to the first numeral of the amount shown by the check, when the pointer is held in place and the edge of the check torn away to form the stub 17. When the stub is formed the pointer is moved to overlie the next numeral of the amount of the check and the tearing again takes place, this operation being repeated until the full amount is shown on the stubs along the margin of the check.

It is apparent that a device of this character may be carried in a pocket checkbook if desired, but in any event would require but a very small space, so that it can be used

for marking personal checks as well as vouchers or the like.

Having thus described my invention what I claim as new therein and desire to secure by Letters-Patent, is:

1. A check marker comprising a straight edge member, having a longitudinal guide rib and an edge flange back-turned and spaced from the body of the member to form a groove, and a pointer having an arched portion movable along the rib and a lip movable in the groove and having frictional contact with the lip, for the purpose set forth.

2. A check marker comprising a straight edge member and a back-turned, yieldable clamp member at one end thereof; said straight edge member having a central, longitudinal guide rib and an edge flange back-turned and spaced from the body to form a groove and a pointer comprising an arched portion movable along the rib and having a lip at one end movable in the groove, and a point at the opposite end extending beyond the edge of the body member for the purpose set forth.

In testimony whereof I affix my signature.

CYRUS W. ELROD.
